(57) **CLAIM**

The ornamental design for a soccer goal net attachment display for stadium soccer goalpost, as shown and described.

DESCRIPTION

FIG. 1 is a front perspective view of a soccer goal net attachment display for stadium soccer goalpost showing my design;

FIG. 2 is a front elevation view thereof;

FIG. 3 is a rear elevation view thereof;

FIG. 4 is a top plan view thereof;

FIG. 5 is a bottom plan view thereof;

FIG. 6 is a right-side elevation view thereof;

FIG. 7 is a left-side elevational view thereof;

FIG. 8 is a rear perspective view thereof;

FIG. 9 is a front perspective view thereof, shown with the soccer stadium goalpost removed for ease of illustration;

FIG. 10 is a front elevation view thereof;

FIG. 11 is a rear elevation view thereof;

FIG. 12 is a top plan view thereof;

FIG. 13 is a bottom plan view thereof;

FIG. 14 is a right-side elevation view thereof;

FIG. 15 is a left-side elevational view thereof;

FIG. 16 is a rear perspective view thereof;

FIG. 17 is an enlarged view of the portion 17 shown in FIG. 1;

FIG. 18 is an enlarged view of the portion 18 shown in FIG. 1;

FIG. 19 is an enlarged view of the portion 19 shown in FIG. 1;

FIG. 20 is an enlarged view of the portion 20 shown in FIG. 3; and,

FIG. 21 is an enlarged view of the portion 21 shown in FIG. 3.

The broken lines in the Figures show portions of the soccer goal net attachment display for stadium soccer goalpost which form no part of the claimed design.

The dash-dash line circles in FIGS. 1, 3, and 17-21 are for the purpose of showing the area of enlargement and form no part of the claim.

1 Claim, 21 Drawing Sheets
